Adolph Henke

United States Patent Office.

A DOLPH HENKEL, OF NEW YORK, N. Y.

Letters Patent No. 88,869, dated April 13, 1869.

IMPROVEMENT IN CARVING-MACHINE.

The Schedule referred to in these Letters Patent and making part of the same.

To all whom it may concern:

Be it known that I, ADOLPH HENKEL, of the city, county, and State of New York, have invented a new and useful Improvement in Carving-Machines, of which the following is a full, clear, and exact description, reference being had to the accompanying drawing, forming part of this specification, and in which—

Figure 1 represents a top view or plan of a carving-machine, constructed in accordance with my invention;

Figure 2, a longitudinal vertical section of the same; and

Figure 3, a transverse section thereof, through the line $z z$, in fig. 2, and looking in direction of the arrow z .

Similar letters of reference indicate corresponding parts.

My improvement relates to carving-machines, in which the cutter, or reducing and carving-tool has its action on or over the work, or body, to be carved, regulated, and directed by the travel of a tracer on or over a pattern corresponding in form to the desired configuration of the carved surface, or article to be made.

Said improvement is applicable to carving on different kinds of material, and for doing different sorts of work, including *bas-reliefs*, busts, &c., and is capable of carving work either larger or smaller than the pattern with which the work, as regards shape of outline, is made to coincide by the travel or action of the tracer.

In this connection, the invention includes a horizontally and vertically-swinging arm, carrying an adjustable tracer and rotating carving-tool, arranged over the work and pattern, which are hung on centres connected with swinging carriers, pivoted to head-stocks that are made capable of a joint sliding movement at different velocities, the whole providing for a universal adjustment of the work and pattern, and of varying the size, or proportions of the work to the pattern in a most perfect and practicable manner.

Referring to the accompanying drawing—

A represents the frame of the machine, which may be of any suitable form.

Said frame carries at its one end a standard, B, on which is mounted a driving-pulley, C, and which serves to carry, by trunnions a , at opposite ends, a cross-rocking shaft, or beam, D.

This rocking-shaft, or beam D, has connected with it, and serves to carry, by a vertical pivot, b, a forwardly-projecting, or extending tracer, and carving-tool arm, or lever E, having a longitudinal slot, c, in it, along which the tracer F and, rotating carving-tool G, or the holders thereof, are adjusted, and their proper set, relatively to each other, determined by a scale, or graduated surface, d, on said arm, according to the size the carved work is required to bear to the pattern.

As the tracer F and carving-tool G are here arranged, the work will be cut, or carved larger than the pattern, but by reversing the positions of these devices; that

is, placing the tracer forward of the carving-tool, the work will be cut smaller than the pattern.

It will suffice here, however, to describe the operation of the machine, with the tracer and carving-tool arranged as shown.

The arm E, carrying these devices, is, by the hang of it, as described, free to swing both vertically and horizontally, in order that the tracer may follow, or travel over the pattern, and the carving-tool have corresponding movements, though differing in degree, give it to cut or shape the work according, as regards outline or configuration, to the pattern. Said arm is moved laterally by the operator in attendance, to make the tracer follow the pattern and carving-tool travel over the surface, article, or body to be carved, the free hang of said arm to adjust itself vertically, serving, at the same time, to allow of these devices rising and falling automatically, according to the outline of the pattern.

The pattern is hung in adjustable centres $e e'$, arranged to project inwardly from or through slides $H H'$, adjustable along slots $f f'$, made in a carrier I, which is pivoted, as at g , so as to admit of its rocking or swinging vertically, in reverse directions, simultaneously on opposite sides of said pivot, by which arrangement the pattern is capable of a varied set in a crosswise direction of the machine, relatively to the tracer, and may be made to assume either a horizontal or angular position, in reverse directions, by swinging the carrier to raise or lower either centre, $e e'$, according to the general or special configuration of the pattern.

This angular set is regulated by means of a curved scale, h, attached to said carrier, and operating in connection with a fixed pointer, or pin, i, attached to a head, or head-stock, J, arranged on the bed of the machine, and to which the carrier I is pivoted for action, as described.

Provision is also made for turning the pattern in an axial direction on its centres $e e'$, by means of a slotted arm, or sub-carrier, k, attached to the one centre-pin, e , and arranged to gear with a pin projecting from the pattern, such turning, or turned set of the pattern being regulated or determined by an index-plate, l, on the back of the centre-pin e , operating in conjunction with a fixed pointer, m.

The head-stock J is also adjustable along the bed of the machine, as hereinafter described.

The work, article, or body to be carved is similarly held and made adjustable by arranging it on centres $e^2 e^3$, projecting from slides $H^2 H^3$, adjustable along slots made in a carrier, I', pivoted as at g' , and provided with a curved scale, h' , operating in connection with a fixed pointer, or pin, the one centre-pin, e' , also being provided with a slotted arm, or sub-carrier, k', that gears with a stud in the end of the work, and said centre-pin, furthermore, being provided with an index-plate, l', operating in conjunction with a fixed pointer, m'.

By means of the index-plates *l l'*, uniformity in the axial set of the work and pattern is secured, while, by means of the curved scales *h h'*, their angular set across the machine is made to conform.

Both head-stocks *J J'* are made conjointly adjustable, or made to slide along the bed of the machine, but in a variable or unequal manner; that is, in the same ratio, as regards speed or distance, as that which the pattern and work bear to each other, in point of size or proportion, and whereby, in the travel of the work and pattern longitudinally, in relation to the bed, as well as in the movement, or movements of the arm *E* over the work and pattern, the same relative actions of the tracer *F* and carving-tool *G*, to accord with the difference in proportions of the work and pattern, are preserved in every direction.

This relative travel of the head-stocks *J J'*, carrying the work and pattern, is effected by turning in either direction, as required, a screw, *L*, that gives motion to the head-stock *J'*, which is connected to the head-stock *J* by a rod, *M*, through the intervention of a lever, *N*, and rod *O*.

This lever *N*, pivoted as at *r*, is graduated on its face, as is also the plate *P*, attached to the head-stock *J*, so that on inserting the rod *O*, or its duplicate, of different length to suit, in any of the holes *s s'*, having corresponding numbers, or marks opposite them, ac-

cording to the relative proportions of the work and pattern, the head-stocks *J* and *J'* are made to travel, on turning the screw *L*, along the bed, in the same relative ratio as the pattern bears to the work, by reason of the action of the screw *L* on the head-stock, *J'* being a direct one, while the movement given through it to the head-stock *J* is an indirect one, and as much slower as the pattern is smaller than the work.

In each and all of these several movements of the tracer and carving-tool over the pattern and work, and of the latter under said tools or devices, the carving-tool is rotated or driven, to effect the necessary cut or reduction, by means of a belt running from the driving-pulley *C* to a pulley, *C'*, on the upper end of the carving-tool *G*.

What is here claimed, and desired to be secured by Letters Patent, is—

The combination, with the horizontally and vertically adjustable, or swinging arm *E*, carrying the tracer and carving-tool, of the head-stocks *J J'*, the screw *L*, the rod *M*, the graduated lever *N*, the rod *O*, and the graduated plate *P*, essentially as described.

ADOLPH HENKEL.
